UNITED STATES PATENT OFFICE

2,436,190

ELECTRIC CIRCUIT BREAKER

Alexander C. Boisseau and Ralph E. Bold, Lansdowne, Pa., assignors to General Electric Company, a corporation of New York

Application November 7, 1944, Serial No. 562,296

8 Claims. (Cl. 200—82)

1

Our invention relates to electric circuit breakers and more particularly to operating mechanisms for electric circuit breakers of the fluid operated type. Specifically, our invention is an improvement on the circuit breaker operating system disclosed and claimed in United States Letters Patent 2,315,991, Thumin, granted April 6, 1943, and assigned to the same assignee as the present application.

Fluid operated circuit breakers have been used quite extensively within the last several years, particularly since the advent of the air blast circuit breakers. Since an air blast circuit breaker requires a source of air under pressure, it is usually advantageous to also utilize this source of air as the source of energy for operating the circuit breaker.

Heretofore, operating mechanisms for fluid operated circuit breakers and particularly fluid operated, fluid blast circuit breakers have been very complicated and expensive.

It is an object of the present invention to provide a new and improved operating mechanism for electric circuit breakers.

It is another object of our invention to provide an operating mechanism for electric circuit breakers which is simple and compact and requires only a fraction of the space and material required by the operating mechanisms used heretofore.

It is another object of our invention to provide an operating mechanism for electric circuit breakers which is simple and compact and which furthermore provides all the functions of retarding, accelerating and operating associated apparatus such as switches, blast valves, and the like.

Further objects and advantages of our invention will become apparent as the following description proceeds and the features of novelty which characterize our invention will be pointed out with particularity in the claims annexed to and forming a part of this specification.

For a better understanding of our invention, reference may be had to the accompanying drawings in which Fig. 1 is a schematic diagram, partly in section, of an electric circuit breaker and operating mechanism therefor with the circuit breaker shown in the closed circuit position; Fig. 2 is a view similar to Fig. 1 showing the circuit breaker in the open circuit position; Fig. 3 is an elevational view, partly in section, of a commercial embodiment of our invention schematically shown in Figs. 1 and 2 with minor modifications; and Fig. 4 is a portion of the embodi-

ment shown in Fig. 3 viewed from the left hand side.

Although our invention is particularly applicable to polyphase circuit breakers, as will become apparent from the description of Figs. 3 and 4 included hereinafter, we have illustrated our invention schematically in Figs. 1 and 2, as applied to a circuit breaker 1, which is illustrated as a single phase circuit breaker of the cross gas blast type. Circuit breaker 1 comprises a stationary contact 2 and a movable contact 3 arranged to be operated so as to draw an arc in arc chute 4. Contacts 2 and 3 are arranged to be connected with suitable line terminals schematically shown at 5 and 6, respectively. The fixed contact 2 is provided with spring pressed contact fingers 7 and longer arcing contact fingers 8, while movable contact 3 is provided with an arcing tip 9 so that when the contacts separate an arc occurs between arcing fingers 8 and arcing tip 9. Immediately after the separation of the contacts one terminal of the arc is transferred by a blast of fluid, such as air, flowing in conduit 10, from contact fingers 8 to a contact 11 which is provided with a tip 12 of arc resistant metal. The fluid blast from conduit 10 upon opening of the circuit breaker 1 drives the arc into the arc chute 4 against the edges of a plurality of partitions or baffles 12, which partitions are transverse to the arc gap and the ends of which extend close to the path of movement of the arcing tip 9 of movable contact 3. The circuit breaker 1 is illustrated by way of example only in order to describe our new and improved operating and control arrangement.

This circuit breaker 1, briefly described above,

is not our invention but is described and claimed in United States Letters Patent 2,284,842, granted June 21, 1942, and assigned to the same assignee as the present application.

In view of the fact that we have illustrated circuit breaker 1 as a fluid blast circuit breaker of the cross air blast type, it is necessary to provide a source of fluid under pressure which is illustrated at 13. Conduit 10 is connected to source 13 through a blast valve 14 having a reciprocally movable valve member 15 fastened to a suitable valve stem 16. A spring 17 normally biases valve member 15 to the closed position indicated in Fig. 1.

Since a source of air or fluid under pressure 13 is necessary for air blast circuit breaker 1, it is desirable to utilize this same source of fluid under pressure to produce the energy for operating the circuit breaker to the open and closed positions. In accordance with our invention we

have provided a simple and compact fluid operated operating mechanism generally indicated at 18. Operating mechanism 18 includes a fluid motor comprising a circuit breaker opening piston 19 and a circuit breaker closing piston 20 rigidly interconnected by a rack 21. Piston 19 is reciprocal in a cylinder 22 while piston 20 is reciprocal in cylinder 23. Preferably these cylinders 22 and 23 are arranged as one continuous cylinder with a discontinuous portion so that a pinion 24 fixedly mounted on a rotatable shaft 25 may engage rack 21. With this arrangement the rectilinear motion of the pistons of the fluid motor is translated into rotary motion of shaft 25.

Cylinder 22 is connected to source 13 through schematically illustrated circuit breaker opening valve 26 and conduit 27. Similarly, cylinder 23 is connected to source 13 through circuit breaker closing valve 28 also schematically shown, and conduit 29. The circuit breaker opening and closing valves 26 and 28, respectively, may be controlled in any suitable manner well known to those skilled in the art and no further discussion thereof will be included herewith.

In order to provide accurate speed control of the fluid motor including pistons 19 and 20, we have provided another set of pistons 30 and 31 rigidly interconnected by a rack 32, which rack also engages pinion 24. Pistons 30 and 31 are mounted in cylinders 33 and 34, respectively, which like cylinders 22 and 23 are preferably arranged as one continuous cylinder, parallel with the continuous cylinder comprising cylinders 22 and 23. It will be obvious that with this arrangement, whenever pistons 19 and 20 are moved to the left, as viewed in Fig. 1, pistons 30 and 31 will be moved to the right by virtue of pinion 24, whose teeth engage with both racks 21 and 32.

Pistons 30 and 31 provide a very desirable means for controlling the speed of operation of the operating mechanism 18 during an operating stroke of the circuit breaker and eliminate the requirement of any separate dashpots or retarding devices as was required in prior art arrangements. Pistons 30 and 31 therefore act as buffers or dashpots to retard the operating mechanism in any desired manner. A suitable spring loaded check valve 35 controls a passageway 36 between cylinders 22 and 33. Similarly, a spring loaded check valve 37 controls a passageway 38 interconnecting cylinders 23 and 34. The size of passageways 36 and 38 and the spring loading of check valves 35 and 37 are arranged so as to charge the associated cylinders 33 and 34 during operating strokes of the circuit breaker to give the desired speed control as will be brought out in greater detail hereinafter. In order to improve the speed control, cylinder 33 is provided with a needle valve 39 leading to atmosphere and cylinder 34 is provided with a needle valve 40, also leading to atmosphere. Although in Figs. 1 and 2 we have illustrated pistons 19 and 20 as being larger than pistons 30 and 31, it should be understood that these pistons may all be the same size as shown in Fig. 3 if desired.

From the description of the operating mechanism 18 above it is obvious that the fluid motor produces rotation of shaft 25 and it is obvious that shaft 25 may be connected to one or more sets of relatively movable contacts to produce relative movement between said contacts.

Rigidly fastened to shaft 25 and rotatable therewith is a crank arm 41. Preferably the free end of crank arm 41 is pivotally connected as in-

dicated at 42 with a link 43, the other end of which is pivotally connected, as indicated at 44 to movable contact 3. Preferably link 43 includes a section 43' of insulating material, and a goose-neck portion 43'' between crank arm 41 and insulation 43'. Straight line motion of movable contact 3 is obtained by means of four guide rollers 45, arranged two on either side of movable contact 3.

10 It will be observed that link 43 and crank arm 41 are arranged so as to provide a toggle arrangement so that with the circuit breaker in the closed position shown in Fig. 1, this toggle is in an over-center position so that any force applied to the

15 contacts tending to open the circuit breaker will have no effect, and fluid under pressure must be provided in cylinder 22 in order to rotate crank arm 41 slightly and move the toggle out of its locking position, or other means for rotating crank arm 41 must be provided.

20 It will be observed that when the circuit breaker is in the open position indicated in Fig. 2, link 43 and crank arm 41 again form an overcenter toggle arrangement with the goose-neck 43'' fitting

25 around shaft 25. Any force applied to movable contact 3 tending to close the circuit breaker will be ineffective and the breaker is effectively locked in the open position requiring movement of piston 20 to release the locking means. The rotation of 30 shaft 25 from open to closed position is somewhat more than 180°.

With our improved operating mechanism the blast valve 14 can readily be operated in response to relative movement of the contacts merely by 35 providing a cam 46 on shaft 25 rotatable with shaft 25. Cam 46 engages with a roller 47 mounted on a bell crank 48 pivotally mounted at 49. Bell crank 48 has an extension 48' engageable with blast valve stem 16. Upon rotation of shaft 25 in a counter-clockwise direction as viewed in Fig. 1, blast valve 14 is opened to provide a blast of fluid under pressure adjacent relatively movable contacts 2 and 3 before these contacts separate sufficiently to draw an arc therebetween. It should be noted that the lift of the blast valve during the opening stroke occurs while the locking toggle is being released and before force is applied to accelerate moving contact blades, thereby maintaining the force required to 50 open the breaker at a minimum.

It should be understood that cutoff switches and the like can be controlled very simply with our new and improved operating mechanism merely by providing additional cams on shaft 25.

55 The operation of the arrangement disclosed in Figs. 1 and 2 will be obvious to those skilled in the art in view of the detailed description included above. If the circuit breaker opening valve 26 is opened, fluid under pressure enters cylinder 60 22 forcing piston 19 to the left, as viewed in Fig. 1. Since piston 19 is mechanically connected by racks 21 and 32 with piston 30, piston 30 must move to the right. Bypass 36 permits air to enter in front of piston 30 which acts as a buffer or dashpot.

65 By proper proportioning of the size of bypass 36 and the strength of the spring of spring-loaded check valve 39, the amount of pre-charging of cylinder 33 can be controlled whereby by the motion of piston 19 can be controlled exactly by the pressure acting on piston 30. It is therefore possible to accelerate the operating mechanism at any reasonable rate and then by precharging cylinder 33, bring the mechanism to a stop without damaging or overstressing the 70 parts. When the circuit breaker has attained its 75

fully open position, indicated in Fig. 2, the toggle arrangement defined by crank arm 41 and link 43 effectively locks the circuit breaker in the closed position. In order to close the circuit breaker, closing valve 38 is opened and the reverse procedure takes place with piston 26 being moved to close the circuit breaker and piston 31 acting as the retarding and speed controlling dashpot depending upon the precharging of cylinder 34 through bypass 30 and spring loaded check valve 37.

In our mechanism, the semicircular stroke of crank 41 cooperates very effectively with the double acting dashpot reaction to bring the moving parts gradually and smoothly to rest in both the closed and open positions; for it will be understood that the crank 41, while approaching either of its toggle positions, is retarding the motion of the vertically moving masses so that the dashpot piston is concerned only in retarding and arresting the movement of the rotating and horizontally reciprocating masses. It will therefore be appreciated that all of the inertia forces of the fast moving masses are effectively distributed and dissipated so that the associated apparatus is substantially free from excessively concentrated shock forces that might be deleterious or hazardous to the equipment.

Although we have disclosed an arrangement in which four pistons are employed in operating mechanism 16, it will be understood that pistons 30 and 31 might be dispensed with and pistons 19 and 20 might alternately function as the operating and retarding pistons, respectively. In view of the more flexible control which may be obtained, the four-piston arrangement disclosed is preferred.

In Figs. 3 and 4 we have illustrated a commercial embodiment of the invention disclosed schematically in Figs. 1 and 2. In Fig. 3 the pistons 30 and 31 have been indicated as of the same diameter as pistons 19 and 20. The corresponding parts of Figs. 3 and 4 are designated by the same reference numerals as in Figs. 1 and 2.

In Figs. 3 and 4 we have illustrated our operating mechanism and circuit breaker as particularly adapted for use with metal clad switchgear and accordingly have disclosed a metal housing 50 from the base of which the arc chute 4 is supported as by an insulator 51. The operating mechanism 16 is mounted on suitable channel irons 52 supported on housing 50 and tank 13 comprising the fluid pressure source is mounted above operating mechanism 16 on suitable supporting means 53.

Between arc chute 4 and operating mechanism 16, housing 50 is provided with a plurality of longitudinally extending ducts 54 and 55 into which the exhaust gases from arc chutes such as 4, may be led as by conduit 56. If the circuit breaker is a three-phase circuit breaker, three conduits 56 will lead into horizontal conduit 51, which in turn will be connected with conduit 55 and suitably connected to atmosphere in a manner disclosed and claimed in Bold Patent No. 2,362,770, granted November 14, 1944, and assigned to the same assignee as the present application.

Housing 50 is provided with a plurality of openings such as 57, one for each of the links 43 which connect crank arms 41 with movable blade contacts 3. Line terminals 3 and 4 are led through the walls of housing 50 through suitable insu-

lators 58 and 59, respectively, and are suitably connected with stationary contacts 2 and 3 by connections 60 and 61, respectively. The rollers 45 for causing movable contact 3 to assume a straight line motion are suitably supported from insulator 52 which in turn is supported from a wall of housing 50.

Fig. 4 clearly illustrates how shaft 28 may be provided with a plurality of crank arms 41 connected to links 43 whereby the various poles of the polyphase circuit breaker may be controlled. It is obvious that with this arrangement a very compact and simple operating mechanism is obtained.

In order that relative movement of the contacts of the circuit breaker may be obtained manually for inspection purposes or the like, the end of shaft 28 is machined to a hexagonal cross section, as is clearly indicated at 63 in Fig. 4, whereby a manual operating lever having a box-wrench end may be applied for manually rotating shaft 28. Under such conditions it is desirable to protect the operator from inadvertent pneumatic operation of the circuit breaker. To accomplish this purpose tank 13 is provided with a blow-down cock 64 directly above the hexagonal end 63 of shaft 28. Cooperating with the handle 65 of blow-down cock 64 is an interference plate 66 which prevents application of the lever having a box-wrench end to the hexagonal portion 63 of shaft 28 unless blow-down cock 64 is open. This insures that no pressure is present in tank 13 whenever the manual lever is applied to shaft 28.

While we have shown and described particular embodiments of our invention, it will be obvious to those skilled in the art that various changes and modifications may be made without departing from our invention in its broader aspects and we, therefore, aim in the appended claims to cover all such changes and modifications as fall within the true spirit and scope of our invention.

What we claim as new and desire to secure by Letters Patent of the United States is:

1. In combination with an electric circuit breaker comprising a pair of relatively movable contacts, an operating mechanism for producing relative movement of said contacts comprising a force applying member adapted to have a substantially rectilinear motion, a rotatable shaft, means for translating the rectilinear motion of said force applying member into rotary motion of said shaft, and means for translating said rotary motion of said shaft into substantially rectilinear motion of one of said contacts, said rotary motion of said shaft extending through an angular travel of more than 180 degrees, said translating means comprising a toggle which at each limiting position of said shaft is in an over-center position for holding said one of said relatively movable contacts in the open and the closed positions respectively.

2. In combination with an electric circuit breaker comprising a pair of relatively movable contacts, an operating mechanism for producing relative movement of said contacts comprising a force applying member adapted to have a substantially rectilinear motion, a rotatable shaft, means for translating the rectilinear motion of said force applying member into rotary motion of said shaft, and means including an arm on said shaft and a link pivotally connected to said arm for translating the rotary motion of said shaft into substantially rectilinear motion of one

of said contacts, the rotary motion of said shaft extending through an angular travel of more than 180 degrees, said arm and link comprising a toggle which at each limiting position of said shaft is in an overcenter position for holding said one of said relatively movable contacts in the open and the closed positions respectively.

3. In combination with an electric circuit breaker comprising a pair of relatively movable contacts, an operating mechanism for producing relative movement of said contacts comprising a force applying member adapted to have a substantially rectilinear motion, a rotatable shaft, means for translating the rectilinear motion of said force applying member into rotary motion 15 of said shaft, means including an arm on said shaft and a link connected to said arm for translating the rotary motion of said shaft into substantially rectilinear motion of one of said contacts, the rotary motion of said shaft extending through an angular travel of more than 180 degrees, said arm and link comprising a toggle which at each limiting position of said shaft is in an overcenter position for holding said one of said relatively movable contacts in the open and the closed positions respectively, and means cooperating with said arm and said link for retarding both the rectilinearly and rotatably moving masses.

4. In combination with an electric circuit breaker comprising a pair of relatively movable contacts, a source of fluid under pressure, means including a blast valve for supplying a blast of fluid adjacent said relatively movable contacts, an operating mechanism for producing relative movement of said contacts comprising a force applying member adapted to have a substantially rectilinear motion, a rotatable shaft means for translating the rectilinear motion of said force applying member into rotary motion of said shaft, means for translating the rotary motion of said shaft into substantially rectilinear motion of one of said contacts, the rotary motion of said shaft extending through an angular travel of more than 180 degrees, said last mentioned means comprising a toggle which at each limiting position of said shaft is in an overcenter position for holding said one of said relatively movable contacts in the open and the closed positions respectively, and means rotatable with said shaft to operate said blast valve.

5. In combination with an electric circuit breaker comprising a pair of relatively movable contacts, an operating mechanism for producing relative movement of said contacts comprising a force applying member adapted to have a substantially rectilinear motion, a rotatable shaft, means for translating the rectilinear motion of said force applying member into rotary motion of said shaft, means for translating the rotary motion of said shaft into substantially rectilinear motion of one of said contacts, the rotary motion of said shaft extending through an angular travel of more than 180 degrees, said last mentioned means comprising a toggle which at 65 each limiting position of said shaft is in an over-

center position for holding said one of said relatively movable contacts in the open and the closed positions respectively, the holding effect of said toggle being released upon initial movement of said force applying member prior to relative movement of said contacts, a source of fluid under pressure, means including a blast valve for supplying a blast of fluid under pressure from said source adjacent said relatively movable contacts during a circuit opening operation of said circuit breaker, and means rotatable with said shaft to open said blast valve while the holding effect of said toggle is released preceding relative separation of said contacts.

6. In combination with an electric circuit breaker comprising a pair of relatively movable contacts, a tank containing fluid under pressure, means including a blast valve for supplying a blast of fluid from said tank adjacent said relatively movable contacts during a circuit opening operation, an operating mechanism for producing relative movement of said contacts comprising a fluid motor connected to said source including a piston, a shaft rotatable in response to movement of said piston means for interconnecting said shaft and one of said contacts, means for manually applying a force to rotate said shaft, and means for preventing a manual force from being applied to said shaft unless substantially no fluid under pressure is present in said tank.

7. In combination with an electric circuit breaker comprising a pair of relatively movable contacts, a tank containing fluid under pressure, 35 an operating mechanism for producing relative movement of said contacts comprising a fluid motor connected to said source, means for manually applying a force to move said contacts, and means for rendering said last mentioned means 40 ineffective to move said contacts unless substantially no fluid under pressure is present in said tank.

8. In combination with an electric circuit breaker comprising a pair of relatively movable contacts, a tank containing a fluid under pressure, an operating mechanism for producing relative movement of said contacts comprising a fluid motor connected to said source, means for manually applying a force to produce relative 45 movement of said contacts, a blow-down cock on said tank, and means for rendering said last mentioned means ineffective unless said blow-down cock is in the open position.
